UNITED STATES PATENT OFFICE.

HUGH F. ELLARD, OF MISSOULA, MONTANA.

CONVEYER CABLE OR ROPE.

1,225,020.

Specification of Letters Patent.

Patented May 8, 1917.

Application filed March 29, 1915. Serial No. 17,910.

To all whom it may concern:

Be it known that I, HUGH F. ELLARD, a citizen of the United States of America, residing at 542 South Third street, west, in the city of Missoula, in the county of Missoula and State of Montana, have invented a new and useful Conveyer Cable or Rope, of which the following is a specification.

My invention contemplates simple and efficient means for transmitting loads by conveyer ropes or cables, having especial reference to such as employ a trail rope connected at one of its ends to the cable and at its other end to the log or other load to be conveyed.

In the accompanying drawing, Figure 1 shows an ordinary conveyer rope or cable to which the feature of my invention may be applied. Figs. 2 and 3 are, respectively, top and edge views of one of the eyelets. Fig. 4 is a detail view of one of the loops and Fig. 5 a detail of the swivel connection between the cable sections. Fig. 6 shows the manner of using a conveyer employing my invention.

As illustrated, the cable 1 is equipped with a series of loops, as 2, which are preferably formed of strands of the rope or other material of which the cable is made. These may be disposed at an angle relative to the longitudinal axis of the cable, as at 3, or they may be disposed parallel thereto as at 4.

I provide each of the loops with a metallic eyelet 5 to maintain the loop against wear. These are preferably woven into the cable.

At the end of each section the cable is provided with a link 6 connecting it with a swivel 7 which in turn is attached to a second section of cable 8.

9 designates the trail rope. It is shown attached to a load, as 10. The trail rope

may be formed with loops 12 having eyelets similar to those described, and the finger link 13 connecting the trail rope to loop 4 of the cable may be like that shown and claimed in my pending application for patent, Serial No. 17,909, filed March 29, 1915, or it may be any other appropriate device permitting of ready attachment and release.

The principal advantages of my invention are that a positive connection is provided between the trail rope and the cable thus preventing the trail rope from slipping along the cable. The security of the connection is materially aided by the eyelets 5. However irregular may be the course over which the cable has to travel it will not become twisted owing to the swivel connections 7 by which the sections of the cable are connected so that the trail rope will always maintain the same relation to the cable and it will exert a steady and even pull upon the load. The tendency of a trail rope to wind up around the conveyer cable is thus effectively prevented.

I claim as my invention:

1. In a cable conveyer, a cable having intermediate its ends a loop formed of strands of its own material, an eyelet in said loop, and a trail rope adapted for attachment to a load and secured to said loop.
2. In a cable conveyer, a cable comprising a series of sections, each having a plurality of loops throughout its length, swivel connections between said sections, and a trail rope adapted for attachment at one of its ends to any of said loops and at its other end to a load.

HUGH F. ELLARD.
